Primary Examiner — John Windmuller*Assistant Examiner* — Steven J Czyz(74) *Attorney, Agent, or Firm* — Northstar Law Group;
Thomas J. Bassolino(57) **CLAIM**

The ornamental design for a baby carrier, as shown and described.

DESCRIPTION

FIG. 1 is a front perspective view of a baby carrier;
FIG. 2 is a front view of the baby carrier shown with environment;

FIG. 3 is a front view of the baby carrier;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a rear perspective view of the baby carrier shown in use in a rear position; and,

FIG. 10 is a front perspective view of the baby carrier shown in use in a front position.

The broken lines depict portions of the article and environment that form no part of the claimed design.
